FISH SCRAPER

Nathan Kaplan, Atlanta, Ga.

Application May 6, 1940, Serial No. 333,641

3 Claims. (Cl. 17—3)

This invention aims to provide a simple machine for scaling a fish, removing the entrails and trimming off the back fin.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in top plan, a fish cleaning machine constructed in accordance with the invention, parts being broken away;

Fig. 2 is a longitudinal section;

Figs. 3 and 5 are cross sections taken, respectively, on the lines 3—3 and 5—5 of Fig. 2;

Fig. 4 is a perspective view showing the guide bar and associated parts;

Fig. 6 is a horizontal sectional view disclosing portions of the chute plates and attendant parts.

The device forming the subject matter of this application comprises a support, including a box-like body 1.

For convenience in locating the relative positions of parts, and for describing the operation, the forward end of the body 1 is marked by the letter A. The rear end of the body 1 is marked by the letter B. The body 1 is carried on corner legs 2.

The body 1 comprises side members 3, a front end member 4 and a rear end member 5. The body 1 of the machine is open at its bottom, as shown at 6, so that scales and guts can drop out.

At its forward end, the body 1 is provided with a front top piece 7. At its rear end, the body 1 is provided with a rear top piece 8. The top piece 8 is somewhat wider than the top piece 7. Vertical, parallel partitions 9 extend between the front end member 4 and the rear end member 5, at the top of the machine. Horizontal brace plates 10 extend the full length of the body and connect the lower edges of the partitions 9 with the side members 3. The brace plates 10 strengthen the partitions 9 (which carry some of the working parts), and they give stability to the entire body 1.

The front end member 4 has an intake opening 11 at its top. The opening 11 is as wide as the distance between the partitions 9, and as high as the distance between the brace plates 10 and the front top piece 7. There is a corresponding discharge opening 12 in the rear end member 5 of the body 1.

A supporting bar 14 extends lengthwise of the body 1, between the front end member 4 and the rear end member 5, and is located in the median plane of the body. An upwardly extended, rearwardly inclined knife 15 is mounted on the bar 14 and is located considerably nearer to the forward end A of the machine than to the rear end B thereof. As the fish is drawn rearwardly, by a means to be described hereinafter, the knife 15 forms a ventral slit in the fish. Near the outlet 12, the bar 14 carries an eviscerator 16, embodying oppositely-disposed, forwardly-inclined parts, converging at their upper ends to a point, as shown in Fig. 5. When the fish is advanced, the eviscerator 16 enters the slit made by the knife 15 and removes the entrails.

As to the means for advancing the fish, a transverse drive shaft 17 is journaled in the side members 3 of the body 1, near the bottom of the body. A hand crank 18 is shown, as a means for rotating the drive shaft 17, but it might be rotated otherwise. A transverse driven shaft 19 is journaled in the side members 3, near the rear end member 5 of the body 1.

A pair of sprocket wheels 20 is secured to the drive shaft 17. The sprocket wheels 20 are located close together, on opposite sides of the bar 14. A pair of sprocket wheels 21 is secured to the driven shaft 19. The sprocket wheels 21 are located close together, on opposite sides of the bar 14. Figure 4 shows, at 22, that the bar 14 is cut away at its ends, to receive the sprocket wheels 21 and the sprocket wheels 20. Each of the sprocket wheels 20 is connected to one of the sprocket wheels 21 by a sprocket chain 23. The wider intermediate portion 50 of the bar 14 (Fig. 4) upholds the upper runs of the sprocket chains 23, and keeps them from sagging. The chains 23 form a fish carrier, and are supplied with vertically extending claws 24. The claws 24, as to the upper runs of the sprocket chains, operate on opposite sides of the knife 15 and have a rearward inclination.

Concavo-convexed chute plates 25 extend lengthwise of the machine, and are located above the upper runs of the sprocket chains 23. At their forward ends, the chute plates 25 are supplied with diverging wings 26, so that a fish may

be introduced readily between them, through the intake opening 11. The chute plates 25 are yieldably mounted in the body 1, for in and out movement, toward and away from the median longitudinal plane of the machine, indicated by the knife 15. With that end in view, the chute plates 25 are supplied with outwardly extended, rigid arms 27, having right line sliding movement in the side members 3 and the partitions 9 of the body 1.

Stop collars 28 are held by set screws 29 on the arms 27, for adjustment longitudinally of the arms. Compression springs 30 surround the arms 27, the springs abutting at their outer ends against the side members 3 of the body 1 and at their inner ends against the stop collars 28. The stop collars 28 engage the partitions 9, to limit the inward movement of the chute plates 25, under the action of the springs 30, but the springs 30 can yield, when a fish is introduced between the chute plates, and they will be forced toward the sides of the fish.

The chute plates 25 have openings 31 in their sides, through which the detached scales pass. Inwardly-inclined and forwardly-extended scale scrapers 32 are mounted on the inner surfaces of the chute plates 25 and overlap the openings 31.

An inverted U-shaped bearing bracket 33 is mounted on the rear top piece 8 of the body 1. The numeral 34 designates a horizontal knife carrier, located below the top member 8 of the body 1, the rear ends of the chute plates 25 being cut away as shown at 35 in Fig. 2, to accommodate the knife carrier. Intermediate its ends, the knife carrier 34 is provided with an upwardly extended, inverted V-shaped saddle knife 36, disposed between the chute plates 25. The purpose of the saddle knife 36 is to fit over the back of a fish and trim off the dorsal fin, as the fish is advanced.

Plungers 37 are mounted for vertical right line reciprocation in the bearing bracket 33 and in the top piece 8. The lower ends of the plungers 37 are connected to the knife carrier 34. Stops 38 are attached to the plungers 37. Compression springs 39 are disposed about the plungers 37 and bear at their upper ends on the top part of the bracket 33, the lower ends of the springs bearing on the stops 38. The stops 38, cooperating with the rear top piece 8, limit the downward movement of the fin-removing saddle knife 36, and the springs 39 hold the knife 36 down on the back of the fish.

The fish to be cleaned is inserted into the machine through the intake opening 11 and is guided between the chute plates 25, by the flared wings 26 of the chute plate. The claws 24 on the sprocket chains 23 engage the fish and advance it between the chute plates 25. The chute plates 25, being yieldably supported by the springs 30, can embrace the fish closely. The scales are removed by the scale scrapers 32 of Fig. 6 and pass outwardly through the openings 31 of the chute plates 25. As the fish is advanced between the chute plates 25, by the action of the chain claws 24, the knife 15 forms a ventral slit. As the fish is about to pass out from between the chute plates 25, at the back end of the machine, the dorsal fin is cut off by the saddle knife 36. The sprocket chains 23 shove the fish out of the machine, through the opening 12. As the fish is being thrust through the opening 12, the eviscerator

16, operating through the ventral slit formed by the knife 15, removes the entrails, the fish being held down by the saddle knife or fin remover 36.

5. The machine is simple in construction, inexpensive to manufacture, not likely to get out of order, and capable of consummating the objects set forth in the opening portion of this specification.

10. Having thus described the invention, what is claimed is:

1. A machine for cleaning fish, comprising a support, oppositely-disposed chute members having scale-outlet openings, scale removers cooperating with the chute members and disposed in operative relation to the openings, means for mounting the chute members on the support for yieldable in and out movement, a slitter carried by the support and projecting between the chute

15 members, a dorsal fin remover disposed near the top of the chute members and near the rear end thereof, means on the support for advancing the fin remover yieldably toward the chute members, an eviscerator on the support near the rear

20 end of the chute members, in line with the slitter, the fin remover being located close enough to the eviscerator so that a fish will be held down by the fin remover whilst the eviscerator is exercising its function, and a carrier on the support

25 and constituting means for advancing a fish with respect to the chute members, the slitter, the fin remover and the eviscerator.

2. A machine for cleaning fish, comprising a support, a fish chute on the support, a slitter carried by the support and projecting into the chute, an eviscerator carried by the support and located behind the slitter and in line therewith, a dorsal fin remover disposed near the top of the chute and near the rear end thereof, and means for mounting the fin remover yieldably on the support, the fin remover being disposed close enough to the eviscerator to hold down a fish whilst the eviscerator is functioning, and means for advancing a fish with respect to the chute, the slitter, the fin remover, and the eviscerator.

3. In a fish-cleaning machine, a frame having at one end an intake for uncleared fish and at the opposite end an outlet for cleaned fish, a reinforcing bar extended longitudinally of the machine from the intake to the outlet, and secured to the end portions of the frame, trough-like chute members disposed on opposite sides of the bar, means for mounting the chute members on the frame for yieldably-resisted outward movement, means for scaling fish as they are advanced between the chute members, a ventral slitter carried by the bar and disposed between the chute members, pairs of sprocket wheels spaced apart longitudinally of the frame, the wheels of each pair being located on opposite sides of the bar, fish-advancing sprocket-chains carried by the wheels and having fish-engaging elements operating between the chute members, the bar being terminally-recessed on both sides, to admit portions of the wheels and to bring them close enough together so that the upper runs of the chains are slidably supported on the intermediate portion of the bar, and means for mounting the wheels on the frame and for actuating the chains.

5. In a fish-cleaning machine, a frame having at one end an intake for uncleared fish and at the opposite end an outlet for cleaned fish, a reinforcing bar extended longitudinally of the machine from the intake to the outlet, and secured to the end portions of the frame, trough-like chute members disposed on opposite sides of the bar, means for mounting the chute members on the frame for yieldably-resisted outward movement, means for scaling fish as they are advanced between the chute members, a ventral slitter carried by the bar and disposed between the chute members, pairs of sprocket wheels spaced apart longitudinally of the frame, the wheels of each pair being located on opposite sides of the bar, fish-advancing sprocket-chains carried by the wheels and having fish-engaging elements operating between the chute members, the bar being terminally-recessed on both sides, to admit portions of the wheels and to bring them close enough together so that the upper runs of the chains are slidably supported on the intermediate portion of the bar, and means for mounting the wheels on the frame and for actuating the chains.

NATHAN KAPLAN.
